UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

PERCUSSIVE FIRING MECHANISM.

1,105,626.

Specification of Letters Patent.

Patented Aug. 4, 1914.

Original application filed October 18, 1913, Serial No. 795,854. Divided and this application filed April 6, 1914. Serial No. 829,828.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in Percussive Firing Mechanism, of which the following is a specification.

This invention relates to percussive firing mechanism for breech loading guns, of the kind in which the striker is released by a trigger or firing handle mounted on the gun carriage.

The chief object of the present invention is to provide improved means whereby the trigger or firing handle can be mounted on a part of the carriage which is not coaxial with the gun trunnions, and the operative relationship between the said trigger or handle and the striker can be maintained notwithstanding the movements of the gun in elevation or depression.

In order that the said invention may be clearly understood and readily carried into effect, we will describe the same more fully with reference to the accompanying drawings, in which:—

Figures 1, 2 and 3 are respectively a side elevation, a partial sectional plan, and a rear elevation showing a constructional form of the invention in which the trigger is carried on the handle of the elevating hand wheel or lever.

A is the gun, B the gun cradle, B' one of the trunnions and C the gun carriage.

D represents the aforesaid device which is pivoted at d to the cradle.

D' is the trigger or firing handle and D² the firing shaft.

E is the elevating hand wheel or lever.

In the example shown, the aforesaid device D is in the form of a curved plate the pivot d of which is arranged parallel to the trunnions and in front thereof when the gun is horizontal.

The firing trigger D' is carried on the handle of the elevating hand wheel or lever E which is mounted on the gun carriage. The said trigger operates through the known arrangement of a sliding pin d³, a lever d⁴ and another sliding pin d⁴ upon an arm d^{4x} on a vertical shaft d⁵ mounted on the

carriage. This shaft has another arm d^{5x} 55 that carries a roller d^{6x} for engaging with the curved plate D. A rod D² is connected to the curved plate D and to a link d² which is in loose contact with a firing arm D^x on the gun. The rod D² is controlled by 60 a spring D^{2x} to hold the parts in the position shown in the drawings.

What we claim and desire to secure by Letters Patent of the United States is:—

1. In percussive firing mechanism for ordnance, the combination with a non-elevating part of the mounting and the gun cradle, of an elevating device on said non-elevating part, a firing trigger on said elevating device, a curved member moved by said trigger 65 and pivotally mounted on the cradle in coaxial relation with the gun trunnions, a striker releasing member on the gun, and means for establishing an operative relationship between these two members. 75

2. In percussive firing mechanism for ordnance, the combination with a non-elevating part of the mounting and the gun cradle, of an elevating device on said non-elevating part, a firing trigger on said elevating device, a curved member moved by said trigger, a pivot for said member carried by the cradle and arranged parallel with the gun trunnions, a striker releasing member on the gun and means for establishing an operative 85 relationship between these two members.

3. In percussive firing mechanism for ordnance, the combination with a non-elevating part of the mounting and the gun cradle, of an elevating device on said non-elevating 90 part, a firing trigger on said elevating device, a curved plate moved by said trigger, a pivot for said plate carried by the cradle and arranged parallel to the gun trunnions, a striker releasing member on the gun, a 95 rod connected to said curved plate and means for connecting said rod to the member on the gun.

4. In percussive firing mechanism for ordnance, the combination with a non-elevating 100 part of the mounting and the gun cradle, of an elevating device on said non-elevating part, a firing trigger on said elevating device, a sliding rod passing through the axis of rotation of the elevating device, a vertical shaft rotatably mounted on the non-elevating part of the mounting, an arm on said shaft against which arm the sliding rod 105

bears, another arm on said shaft, a roller on the last mentioned arm, a curved plate against which said roller bears, a pivot for said plate carried by the cradle and arranged 5 parallel to the gun trunnions, a striker releasing member on the gun, a rod connected to said curved plate and means for connecting said rod to the member on the gun.

5. In percussive firing mechanism for ord-
10 nance, the combination with a non-elevating part of the mounting and the gun cradle, of an elevating device on said non-elevating part, a firing trigger on said elevating de-
vice, a curved plate moved by said trigger, a pivot for said plate carried by the cradle and arranged parallel to the gun trunnions, 15 a striker releasing arm on the gun, a lever in contact with said arm and means for connecting said lever to the curved plate on the
20 cradle.

6. In percussive firing mechanism for ord-
25 nance, the combination with a non-elevating part of the mounting and the gun cradle, of an elevating device on said non-elevating part, a firing trigger on said elevating de-
vice, a curved plate moved by said trigger, a pivot for said plate carried by the cradle and arranged parallel to the gun trunnions, 30 a striker releasing arm on the gun, a lever in contact with said arm, and a rod for con-necting said lever to the curved plate on the cradle.

In testimony whereof we affix our signatures in presence of two witnesses.

ARTHUR TREVOR DAWSON,
GEORGE THOMAS BUCKHAM.
